(57) **CLAIM**

The ornamental design for an out-the-front knife, as shown and described.

DESCRIPTION

FIG. 1 is a right perspective view of an out-the-front knife embodying the new design;

FIG. 2 is a left perspective view of the out-the-front knife; FIG. 3 is a right side elevation view of the out-the-front knife;

FIG. 4 is a left side elevation view of the out-the-front knife; FIG. 5 is a top side elevation view of the out-the-front knife; FIG. 6 is a bottom side elevation view of the out-the-front knife;

FIG. 7 is a front side elevation view of the out-the-front knife; and,

FIG. 8 is a rear side elevation view of the out-the-front knife. The broken lines depict portions of the out-the-front knife that form no part of the claimed design.

1 Claim, 4 Drawing Sheets
